WRITING IMPLEMENT HOLDER FOR A TELEPHONE

George Bryce, 8400 Artesian, Detroit, Mich. 48228

Filed Mar. 23, 1972, Ser. No. 237,608

Term of patent 14 years

Int. Cl. D14—03

U.S. Cl. 26—14 A

FIGURE 1

FIGURE 6

FIG. 1 is a front perspective view of a writing implement holder for a telephone showing my new design adapted to fit in the cradle of a telephone;

FIG. 2 is a front elevational view thereof;

FIG. 3 is a side elevational view thereof;

FIG. 4 is a front perspective view of another embodiment of the writing implement holder for a telephone shown in FIG. 1 adapted to fit on the front of a wall telephone;

FIG. 5 is a front elevational view thereof; and

FIG. 6 is a side elevational view thereof.

I claim:

The ornamental design for a writing implement holder for a telephone, as shown and described.
